A. J. Sauer.

Inventor:
Ben K. Ford
By Walter M. Fuller
Atty.

UNITED STATES PATENT OFFICE.

BEN K. FORD, OF OAK PARK, ILLINOIS, ASSIGNOR TO UNION BED AND SPRING COMPANY, OF CHICAGO, ILLINOIS, A CORPORATION OF ILLINOIS.

BEDSPRING FRAME.

Application filed November 4, 1922. Serial No. 598,992.

To all whom it may concern:

Be it known that I, BEN KING FORD, a citizen of the United States, residing at Oak Park, in the county of Cook and State of Illinois, have invented certain new and useful Improvements in Bedspring Frames, of which the following is a specification.

My invention pertains to novel, structural and functional characteristics in the means 10 for mounting or supporting bed-spring frames on bedsteads.

One aim of the invention is to provide a construction of this character which can be produced or manufactured at relatively 15 small expense and at substantially less cost than has heretofore been feasible.

The invention concerns particularly the means, preferably adjustable, for resting on the bedstead side rails whereby to support 20 or carry the bed-spring frame as a whole, such frame being carried by suitable springs constituting a yielding or cushion mounting.

Another advantage of the improved structure resides in its capacity for reversal, that 25 is right and left hand use, so that one style only of mounting need be employed, although several are used in the complete construction.

A further aim of the invention is to supply a device or appliance of this kind which 30 is simple in structure, which is positive-locking, which performs its functions efficiently, and which is unlikely to become injured or damaged in ordinary service.

To the accomplishment of these and other desirable ends, I have produced the appliance representing a preferred embodiment of the invention illustrated in the accompanying drawing to which reference should be had in connection with the following detailed description and throughout the several views of which like reference characters refer to the same parts.

In this drawing:

Figure 1 is a partial side elevation of the improved bed-spring and its frame showing a portion of one of the bedstead side rails;

Figure 2 is an enlarged horizontal section on line 2-2 of Figure 1, the parts being viewed in the direction indicated by the arrows;

Figure 3 is an enlarged vertical cross-

section on line 3-3 of Figure 1, the parts being viewed as shown by the arrows;

Figure 4 is an end view of the mounting 55 for supporting the bed-spring frame on the bedstead; and

Figure 5 is a vertical cross section on line 5-5 of Figure 3.

Turning to the several views of this drawing, it will be readily perceived that the cylindrical, tubular or hollow side-bar 10 of the bed-spring frame is equipped at each end (only one being shown) with a cast-metal standard or bracket 11 on the corresponding ones of which an appropriate cross or end bar 12 is mounted in the usual way, the metallic fabric 13 for the bed-spring being connected to such bar by means of the customary, horizontal, helical springs 14. 60

Near each end of the bed-spring frame and above its tubular side-bars 10 there is a hollow or tubular cross-bar 15, each end of which is equipped with a cap or closure 16. 65

Above each frame element 10 each such 70 member 15 is encased in a sheet-metal sleeve 17 of inverted U-shape, the parallel legs of such part extending down through slots 18 in a sheet-metal plate 19 and having their portions 20 and 21 below such plate bent 75 outwardly in opposite directions to securely fasten the elements rigidly together.

Thus these united parts form a socket 80 slidably accommodating the tube or hollow rod 15. 85

The plate 19 has downturned ends or depending flanges 22 and 23 equipped with registering or aligned horizontal slots 24 and 25 receiving a flat bar 26 supplied with integral outstanding ears or lugs 27, 27 to 90 limit the amount of lengthwise play of the bar in the slots and to prevent its withdrawal.

As is clearly depicted in the drawing, the outstanding part of such bar is designed to 95 rest on the top face of the bedstead side-rail 28, which in the present instance is shown as being of angle cross-section.

The slot 24 at the center of its top margin has a downwardly-projecting tooth or lug 100 29 adapted to fit in any one of a series or group of aligned holes or perforations 30 along the center of bar 26 to maintain the latter in adjusted position with the proper

portion thereof projecting outwardly over the side-rail of the bedstead.

Such capacity for ready adjustment enables the bed-spring to be used with facility 5 on bedsteads of different transverse dimensions, that is to say, those whose side-rails are spaced apart different distances.

The element 19 is considerably wider than the flat bar 26, as shown in Figure 2, and 10 the two opposite side portions of the former are each supplied with three spaced holes, 31, 32, 33—34, 35, 36, the middle one 32 and 35 of each group being disposed centrally of the plate.

15 Such apertured plate 19 is connected to the corresponding standard or bracket 11 by a pair of parallel, substantially-horizontal coil-springs 37 and 38, the opposite hook ends of which take into the holes 31 20 and 32 and loops or eyes 39 and 40 of a fastener 41 mounted on the bracket in any convenient or approved fashion.

The center hole 35 at the other side of the plate receives the hook end of a long rod or 25 wire 42 fastened in like manner to the companion hole of the other plate at the opposite end of the bed-spring.

These two somewhat-flexible rods or wires 30 42 at the opposite sides of the bed-spring and of which only a fragment of one is shown in the drawing support a plurality of upright spiral-springs 43 in a well known manner positioned beneath the center portion or section of the fabric 13 to yieldingly 35 support the latter against undue sagging or deflection.

Thus the two cross members 15 at the opposite ends of the bed-spring through the adjustable end structures described rest at 40 their opposite ends on the side-rails of the bedstead and the bed-spring as a whole is yieldingly or floatingly supported on these by the springs 37 and 38 and in part by the wires 42 which assist in carrying the central 45 portion of the bed-spring and its load through the spiral-springs 43.

The weight of the bed-spring maintains the tongue or finger 29 in the selected hole 30 thus assuring the desired position of the plate or flat bar 26, but if at any time it is required to change the adjustment of such element, this may be easily accomplished by temporarily removing the load from such bar and positioning it lengthwise in the required place in which it will thereafter be maintained by the locking lug 29.

It will be seen that by providing each side of the part 19 with three holes, the whole supporting structure comprising the 60 associated elements 17, 19 and 26, may be used at either end of either side of the bed-spring, the appropriate holes being used for the attachment of the helical springs and the wire, whereby there is no need of making right and left hand structures.

Thus this invention supplies a simple, adjustable appliance composed of few parts readily assembled, the production of which device may be effected at comparatively 70 small cost.

The invention is not limited and restricted to the precise and exact details of construction shown and described and these may be modified within comparatively wide 75 limits without departure from the heart and essence of the invention and without the sacrifice of any of its substantial benefits and advantages.

I claim:

1. A mounting for a bed-spring frame 80 adapted to rest on a bedstead side rail, comprising in combination, a sheet-metal plate element of the bed-spring frame having depending slotted end flanges, a supporting bar adjustable in the slots of said flanges and designed to bear on the bedstead side-rail, a transverse element of the bed-spring frame, a sheet-metal socket member receiving said transverse element and having legs 85 extended down through holes of said plate and bent over thereunder to fasten the parts together.

2. A mounting for a bed-spring frame adapted to rest on a bedstead side-rail, comprising in combination, a plate having depending slotted end flanges, one of said slots having a locking tongue integral with the flange projecting into such slot, a supporting bar adjustable in said flange slots and having a series of holes, any one of which is adapted to receive said tongue to maintain the bar in adjusted position, a transverse element of the bed-spring, and means mounting 95 said plate and bar on said element.

3. A mounting for a bed-spring frame adapted to rest on a bedstead side-rail, comprising in combination, a plate having depending slotted end flanges, one of said slots having a locking tongue integral with the flange projecting into such slot, a supporting bar adjustable in said flange slots and having a series of holes any one of which is adapted to receive said tongue to maintain the bar in adjusted position, a transverse element of the bed-spring, a sheet-metal 110 socket member receiving said transverse element and having legs extended down through holes of said plate and bent over thereunder to fasten the parts together.

4. In a bed-spring structure of the character described, the combination of a side-bar for the bed-spring frame, an end bracket secured to said side-bar, a cross end bar mounted on said bracket, a metallic fabric fastened to said end bar, a spiral spring 125 structure supporting the central part of said fabric, a plate having downturned slotted end flanges and provided along each of its opposite sides with three holes, a pair of springs connected to said bracket and hav- 130

ing ends taking in the end holes at one side of said plate, a flexible wire fastened in the middle hole of the group of three at the other side of said plate and assisting in carrying said spiral spring structure, and a flat supporting bar adjustable in said flange slots and adapted to rest on the bedstead side-rail.

5. In a bed-spring structure of the character described, the combination of a side-bar for said bed-spring frame, a bracket secured to the end of said side-bar, a transverse end bar mounted on said bracket, a metallic fabric fastened to said end bar, a spiral spring structure beneath and supporting the central part of said fabric, a plate provided along each of its opposite sides with three holes, a pair of springs connected to said bracket and having ends taking in the end holes at one side of said plate, a flexible wire fastened in the middle hole of the group of three at the other side of said plate and assisting in carrying said spiral spring structure, and a bar adjustable on said plate and adapted to rest on the bedstead side-rail.

6. In a bed-spring structure of the char-

acter described, the combination of a side-bar for the bed-spring frame, a bracket secured to an end of said side-bar, a transverse end bar mounted on said bracket, a metallic fabric fastened to said end bar, a spiral spring structure underlying and supporting the central part of said fabric, a plate having downturned slotted end flanges and provided along each of its opposite sides with three holes, a pair of springs connected to said bracket and having ends taking in the end holes at one side of said plate, a flexible wire fastened in the middle hole of the group of three at the other side of said plate and assisting in carrying said spiral spring structure, a flat supporting bar adjustable in said flange slots and adapted to rest on the bedstead side-rail, and a tongue on one of said flanges projecting downwardly into its slot and adapted to fit in any one of a series of holes in said flat supporting bar to maintain the latter in adjusted position.

In witness whereof I have hereunto set my hand and seal.

BEN K. FORD. [L.S.]
